UNITED STATES PATENT OFFICE.

BENJAMIN C. ODELL, OF KINGSTON, NEW YORK, ASSIGNOR TO THOMPSON,
PERLEY & WAITE, OF BALDWINSVILLE, MASSACHUSETTS.

NURSERY-CHAIR.

SPECIFICATION forming part of Letters Patent No. 317,180, dated May 5, 1885.

Application filed May 20, 1884. (No model.)

To all whom it may concern:

Be it known that I, BENJAMIN C. ODELL, of 5
Kingston, in the county of Ulster and State of
New York, have invented a new and useful
Improvement in Nursery-Chairs; and I do
hereby declare that the following is a full,
clear, and exact description of the same.

My invention is an improvement in chil- 10
dren's nursery-chairs of that class in which the
chair is capable of adjustment into a carriage.
The general form of the chair is the same as that
shown in applications filed by me in the United
States Patent Office on the 2d day of June, 1882, and 15
23d day of January, 1884, respect-
ively, and parts and combinations herein
shown and not claimed are claimed in said
applications.

The invention consists, first, of a foot-rest 20
and carriage-extension pivoted upon the for-
ward pair of pivoted legs, and adapted to be
turned up to serve as a foot-rest when the
chair is in its high position, and also adapted
to be turned down to constitute in part the 25
forward end of the body of the carriage when
the chair is converted to that form.

It also consists of side pieces or guards fixed
to the forward legs, and forming, with the said
foot-rest and extension, the forward part of
the carriage.

30 In the accompanying drawings I have shown
the best known embodiment of my invention.

In these drawings, Figure 1 represents in
perspective the structure arranged as a chair.
Fig. 2 shows the same in central section ar-
35 ranged as a carriage. Fig. 3 represents a front
view of the two front legs with the foot-rest
and extension attached and in lowered posi-
tion, the side pieces being omitted. Fig. 4
shows the locking-bolt of the foot-rest.

40 The legs A A and B B are pivoted to the
chair-bottom and to each other, as shown.
Those of each pair are connected by cross-bars
a. The push-handles C C are pivoted at their
lower ends to the rear legs, and are connected
45 to the back of the chair by links c. The wheels
D and d are pivoted, the former on the rear
and the latter on the front legs. All the parts
as above explained are as shown in my afore-
said applications. Between the front legs I
50 pivot the foot-rest and carriage-front E by
means of a rod or wire extended across from

one leg to the other at the point e. The sides
of this foot-rest and extension are substan-
tially triangular in shape, the pivot being at
the apex. These sides (marked f f) form in 55
part the sides of the extension or front part of
the carriage when the structure is in the posi-
tion shown in Fig. 2. The front part, g, forms
the front of the carriage-extension when in the
position of Fig. 2, and the top of the foot-rest 60
when in the position of Fig. 1. The front
h (shown in the position of Fig. 1) forms
the bottom of the carriage-front in Fig. 2. I
have shown this foot-rest and carriage-exten- 65
sion as formed with rattan and reed-work, and
this in the kind of carriage shown is the pre-
ferred form, but may be made with any other
suitable material. When this part is down in
the position shown in Fig. 3, it may rest upon
the cross-bar k, or upon any suitable stud set 70
on the legs.

When the chair is in the form in Fig. 1, the
foot-rest is held by means of a gravity lock-
ing-bolt, l, which catches in the loop or hole
m in the edge of the foot-rest. This is set 75
loosely in the cross-bar k, and is held by guards
against being wholly withdrawn. The upper
part furnishes a hole for the hand, whereby it
may be raised and its weight return it in
position.

80 In order to complete the carriage-front and
form therein a proper receptacle for the feet
of the occupant and the necessary covering or
cushions, I fix to the front legs side pieces, F
F, and in the form of chair shown I prefer to 85
make this of rattan and reed-work, as repre-
sented in the figures. They are so set as to
give the foot-rest and carriage-extension space
to move freely, and when this part is down
form the extension, and they constitute the 90
sides, as represented in Fig. 2. The front h
forms only a part of the bottom between the
front legs. The rest is formed by rattan and
reed-work, (shown at n, Fig. 3,) which work
is between the legs; or it may be formed by a 95
plain or ornamented thin piece of board. The
seat is formed with rattan and reed-work, top
and arms, as represented in the figures, this
work being set upon a solid frame of the seat,
and its structure gives a uniform and sym- 100
metrical appearance to the carriage when it is
adjusted, as shown in Fig. 2.

I do not limit myself to the precise form of pivoted legs shown, as my invention will be applied to other forms of chairs.

I claim as my invention—

- 5 1. The combination, in a chair of the class described, of pivoted front legs, a foot-rest, and a carriage-extension pivoted upon the said legs, substantially as described.
- 10 2. The combination, in a chair of the class described, of the front legs, the foot-rest, and carriage-extension pivoted upon said legs, and the side piece or guards, FF, substantially as described.

3. The combination, in a chair of the class described, of the legs, the foot-rest, and carriage-extension pivoted upon said legs, and the gravity-bolt *l*, set in the cross-bar *t*, substantially as described.

In testimony whereof I have signed my name to this specification in the presence of two subscribing witnesses.

BENJ. C. ODELL.
